Related U.S. Appl. No. 29/294,256, filed Dec. 31, 2007; Inventor: Keiji Okada; Title: Transitional Image for a Portion of a Display Screen of a Digital Camera.

Primary Examiner—Cathron C Brooks*Assistant Examiner*—Deanna Fluegeman(74) *Attorney, Agent, or Firm*—Frishauf, Holtz, Goodman & Chick, P.C.(57) **CLAIM**

The ornamental design for a transitional image for a portion of a display screen of a digital camera, as shown and described.

DESCRIPTION

FIG. 1 is a front view of a transitional image for a portion of a display screen of a digital camera, showing my new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof; and,

FIG. 11 is a front view of an eleventh image thereof.

The appearance of the transitional image sequentially transitions between images shown in FIGS. 1-11. The process or period in which one image changes into another forms no part of the claimed design. The broken line showing of a portion of a display screen and of a camera in all views is for illustrative purposes only and forms no part of the claimed design.
